(57) **ABSTRACT**

A stud rail system comprising at least one stud rail assembly. The at least one stud rail assembly comprises a plurality of rail portions, a plurality of cross portions, where a plurality of sets of support openings are formed in each of the plurality of the cross portions, a plurality of pin projections, where each rail portion supports at least one pin projection, a plurality of support assemblies, and a plurality of support projections, where each support projection is supported by one of the plurality of support assemblies. Each of the support projections extends through one of the support openings in each set of support openings such that the rail portions are rotatably connected to cross portions at a plurality of axis points to allow the stud rail assembly to be reconfigured between a collapsed configuration and an expanded configuration.

STUD RAIL SYSTEMS AND METHODS FOR USE IN REINFORCED CONCRETE STRUCTURES

RELATED APPLICATIONS

This application, U.S. patent application Ser. No. 18/635,558 filed April 15, 2025 is a continuation of U.S. patent application Ser. No. 17/650,139 filed Feb. 7, 2022, now U.S. Pat. No. 11,959,270 which issued on Apr. 16, 2024.

U.S. patent application Ser. No. 17/650,139 filed Feb. 7, 2022, claims benefit of U.S. Provisional Application Ser. No. 63/175,964 filed Apr. 16, 2021, the contents of which are incorporated herein by reference.

TECHNICAL FIELD

The present invention relates to stud rail systems and methods for concrete structures and, more specifically, to stud rail systems and methods for reinforcing concrete structures at a column.

BACKGROUND

Metal such as steel is conventionally embedded in wet concrete to reinforce the concrete after the concrete has cured to strengthen the resulting reinforced concrete structure. Metal reinforcement structures can be in a variety of sizes and configurations, such as bars (rebar), cages, cables, and like, that are engineered to yield a reinforced concrete structure meeting predetermined structural requirements.

A stud rail system particular form of metal structure used to reinforce the juncture of horizontal concrete structures, such as beams and/or decks, to vertical concrete structures, such as columns and/or piles. Stud rails conventionally comprise flat bar stock to which pins are welded.

Stud rails are typically engineered for use at a specific location within a larger reinforced concrete structure, and the larger structure may comprise multiple configurations of stud rails depending on the structural requirements of each specific location within the larger structure. Improperly assembling and/or securing one or more stud rails can compromise the structural integrity of the entire reinforced concrete structure. Further, conventional methods of properly fabricating, assembling, and securing stud rails can be time consuming and thus costly.

The need thus exists for improved stud rail systems and methods that are easier to assemble and minimize the likelihood of improper assembly and/or securing of the stud rail(s) during the process of forming at least a portion of a reinforced concrete structure.

SUMMARY

The present invention may be embodied as a stud rail system for a reinforced concrete structure defining a column portion and a slab portion, the stud rail system comprising at least one stud rail assembly. The at least one stud rail assembly comprises a plurality of rail portions, a plurality of cross portions, where a plurality of sets of support openings are formed in each of the plurality of the cross portions, a plurality of pin projections, where each rail portion supports at least one pin projection, a plurality of support assemblies, and a plurality of support projections, where each support projection is supported by one of the plurality of support assemblies. Each of the support projections extends through one of the support openings in each set of support openings

such that the rail portions are rotatably connected to cross portions at a plurality of axis points to allow the stud rail assembly to be reconfigured between a collapsed configuration and an expanded configuration. Before and during 5 pouring of concrete to form the slab portion, the at least one stud rail assembly is arranged at a desired location and orientation relative to the column portion. When supported at the desired location and orientation during pouring of the concrete slab portion, the at least one stud rail assembly is 10 arranged within the slab portion such that at least the cross members, the pin projections, the support projections, and the support openings of each stud assembly are outside an area above the column portion.

The present invention may also be embodied as a method 15 of reinforcing a concrete structure comprising a column portion and a slab portion, the method comprising the following steps. A form, a plurality of rail portions, and a plurality of cross portions are provided. A plurality of sets of support openings are formed in each of the plurality of the cross portions. A plurality of pin projections are formed on each of the plurality of rail portions. A plurality of support assemblies and a plurality of support projections are provided. Each support projection is supported by one of the plurality of support assemblies. At least one stud rail assembly 20 is formed by arranging each of the plurality of support projections within one of the support openings of each set of support openings such that the rail portions are rotatably connected to the cross portions at a plurality of axis points to allow the stud rail assembly to be reconfigured between a collapsed configuration and an expanded configuration. Before and during 25 pouring of concrete to form the slab portion, the at least one stud rail assembly is arranged such that the at least one stud rail assembly is supported at a desired location and orientation relative to the column portion. Concrete is arranged on the form around the stud rail system in the desired location and orientation to form the slab portion such that at least the cross members, the pin projections, the support projections, and the support openings of each stud assembly are outside an area above the 30 column portion.

The present invention may also be embodied as a reinforced concrete structure comprising a column portion, a slab portion, and a stud system. The stud system comprises a plurality of stud rail assemblies. Each of the plurality of stud rail assemblies comprises a plurality of rail portions, a plurality of cross portions, where a plurality of sets of support openings are formed in each of the plurality of the cross portions, a plurality of pin projections each supported by one of the plurality of rail portions, a plurality of support assemblies, and a plurality of support projections, where each of the support assemblies supports one of the plurality of support projections. Each of the support projections extends through one of the support openings in each set of support openings such that the rail portions are rotatably connected to the cross portions at a plurality of axis points to allow the stud rail assembly to be reconfigured between a collapsed configuration and an expanded configuration. Before and during 40 pouring of concrete to form the slab portion, the stud system is arranged to support the plurality of stud rail assemblies at desired locations and orientations relative to the column portion. When supported at the desired locations and orientations during pouring of the concrete slab portion, the plurality of stud rail assemblies is arranged within the slab portion such that at least the cross members, the pin projections, the support projections, and the support openings of each stud assembly are outside an area above the 45 column portion.

BRIEF DESCRIPTION OF THE DRAWINGS

FIG. 1 is a perspective view of a first example stud rail system of the present invention secured in a desired orientation and at a desired location relative to an example first stage structure comprising an example first column portion and an example form;

FIG. 2A is a side elevation view of the example first stage structure prior to placement of the first example stud rail system;

FIG. 2B is a top plan view of the example first stage structure prior to placement of the first example stud rail system;

FIG. 3A is a side elevation view of a first step in the process of arranging the first example stud rail system relative to the example first stage structure;

FIG. 3B is a top plan view of the first step in the process of arranging the first example stud rail system relative to the example first stage structure;

FIG. 4A is a side elevation view of a second step in the process of arranging the first example stud rail system relative to the example first stage structure;

FIG. 4B is a top plan view of the second step in the process of arranging the first example stud rail system relative to the example first stage structure;

FIG. 5A is a side elevation view of a process of pouring concrete on the example first stage structure and around the first example stud rail system to form an example second stage structure;

FIG. 5B is a top plan view of the process of pouring concrete on the example first stage structure and around the first example stud rail system to form an example second stage structure;

FIG. 6A is a side elevation view of forming an example third stage structure comprising a second column portion on the example second stage structure;

FIG. 6B is a top plan view of forming the example third stage structure comprising a second column portion on the example second stage structure;

FIG. 7 is a perspective view of an example first stud rail assembly forming part of the first stud rail system, the example first stud rail assembly being depicted in an expanded configuration;

FIG. 8 is a top perspective exploded view of the example first stud rail assembly;

FIG. 9 is a side elevation view of the example first stud rail assembly, the example first stud rail assembly being depicted in an expanded configuration;

FIG. 10 is a top plan view of the example first stud rail assembly, the example first stud rail assembly being depicted in an expanded configuration;

FIG. 11 is a perspective view of an example first stud rail assembly forming part of the first stud rail system, the example first stud rail assembly being depicted in a collapsed configuration;

FIG. 12 is a perspective view of an example support member that may be used by the example first stud rail assembly; and,

FIG. 13 is a perspective detail view of a portion of FIG. 7 illustrating the example support assembly of the example first stud rail assembly.

DETAILED DESCRIPTION

FIG. 1 is a perspective view of a first example stud rail system 20 constructed in accordance with, and embodying, the principles of the present invention. In FIG. 1, the first

example stud rail system 20 secured relative to an example first column portion 22 and an example form 24. As is conventional, the example first column portion 22 comprises a column rebar structure 26, and the example form 24 defines a form upper surface 28. The first example stud rail system 20 and the first column portion 22 form at least a portion of a completed reinforced concrete structure 30 as depicted in FIGS. 6A and 6B.

FIGS. 1, 2A, and 2B illustrate that the example first column portion 22 forms an example first stage structure 32, and the example form 26 is supported such that the form upper surface 28 is in a desired location and orientation relative to the example first stage structure 32 in a conventional manner. Further, the example column rebar structure 26 extends from the first column portion 22 beyond (e.g., above) the form upper surface 28 of the example form 24. FIGS. 2A and 2B illustrate a first step in the process of forming the completed reinforced concrete structure 30.

With the example form 24 supported in the desired location and the desired orientation relative to the example first stage structure 32, the first example stud rail system 20 is arranged at least partly above one or both of the example form 24 and the example first stage structure 32. In particular, the first example stud rail system is reconfigured from a collapsed configuration (FIGS. 3A and 3B) to an expanded configuration (FIGS. 4A and 4B) in a desired location and in a desired orientation relative to the example form 24 and the example first stage structure 32. A second stage structure 34 is then formed by pouring a slab 36 on top of the example form 24 and the example first stage structure 32 as shown in FIGS. 5A and 5B. After the slab 36 is cured to form the example second stage structure 34, an example second column portion 38 is poured to form the completed reinforced concrete structure 30 as shown in FIGS. 6A and 6B.

With the foregoing general description of the construction and operation of the present invention in mind, the details of the first example stud rail system 20 will now be described in further detail. In the following discussion, reference characters without appended letters generally refer to components identified by such reference characters, while reference characters with appended letters refer to a specific component of the type identified by reference characters without appended letters. The use of reference characters with and without appended letters thus does not indicate different components.

The first example stud rail system 20 depicted and described herein is an example that has been engineered to reinforce the completed concrete structure 30. However, a stud rail system of the present invention may take forms other than the first example stud rail system. For example, another embodiment of a stud rail system of the present invention designed for use in a different reinforced concrete structure may be embodied in sizes and configurations other than those of the first example stud rail system 20.

In particular, the first example stud rail system 20 comprises first, second, third, and fourth stud rail assemblies 40a, 40b, 40c, and 40d. The example stud rail assemblies 40a, 40b, 40c, and 40d are the same. However, the stud rail assemblies 40a, 40b, 40c, and 40d forming a stud rail system 20 of the present invention need not be the same, and stud rail assemblies of the present invention may be embodied in sizes and configurations other than those of the example stud rail assemblies 40a, 40b, 40c, and 40d. In the following discussion, the reference character 40 will be used to refer to any one of the example stud rail assemblies 40a, 40b, 40c, and 40d.

As perhaps best shown in FIG. 7, each stud rail assembly 40 comprises a plurality of rail portions 50, a plurality of cross portions 52, and a plurality of support assemblies 54. In particular, the example stud rail assembly 40 comprises first, second, and third rail portions 50a, 50b, and 50c, first and second cross portions 52a and 52b, and first, second, third, fourth, fifth, and sixth support assemblies 54a, 54b, 54c, 54d, 54e, and 54f. Stud rail assemblies with different numbers of rail portions and cross portions may be used depending on the structural requirements of the completed reinforced concrete structure 30.

Each of the plurality rail portion(s) 50 defines at least one pin projection 60 comprising a rod portion 62 and a cap portion 64 and at least one support projection 70 configured to engage one or more of the support assemblies 54. The example rod portion(s) 62 is(are) cylinders having a first diameter, and the example cap portion(s) 64 is(are) discs defining a second diameter that is greater than the first diameter. The example pin projections 60 are all the same and, as depicted, may be conventional but may take different sizes, shapes, and configurations as required by the structural requirements of the completed reinforced concrete structure 30.

The example support projection 70 may take any form appropriate to allow at least one of the plurality support assemblies 54 to be permanently or detachably attached to the plurality rail portion(s) 50, and thus to the stud rail assembly 40, as will be described in further detail below. The example support projection 70 defines a threaded external surface 72 adapted to detachably attach one of the plurality of support assemblies 54 to the stud rail assembly 40 as will be described in further detail below.

Each of the plurality of cross portion(s) 52 defines at least one support opening 80 for each of the plurality of rail portion(s) 50. To form the example stud rail assembly 40, each of the example support projection(s) 70 is passed in a first direction through one of the support openings 80, and one of the plurality of support assemblies 54 is secured to each of the support projection(s) 70. The plurality of support assemblies 54 inhibit or prevent movement of the support projection(s) 70 in a second direction opposite the first direction. However, the support projection(s) 70 each form an axle 74 that allows pivoting movement of the rail portion(s) 50 relative to the cross portion(s) 52.

The engagement of at least one of the plurality of support assembly(ies) 54 with the support projection(s) 70 thus secures the plurality of cross portion(s) 52 to the plurality of rail portion(s) 50 to form the example stud rail assembly 40. With proper arrangement of the support projection(s) 70 and the support opening(s) 80, the pivoting movement allowed between the plurality of rail portion(s) 50 and plurality of the cross portion(s) 52 allows the example stud rail assembly 40 to be reconfigured between a collapsed or folded configuration as depicted in FIGS. 3A, 3B, and 11 and an expanded or open configuration as depicted in FIGS. 4A, 4B, 7, and 10.

In particular, with the example stud rail assembly 40 in the expanded or open configuration as shown in FIG. 10, the example support projection(s) 70 and the example support openings 80 are configured and located in a symmetrical grid 90 comprising the intersections 92 of a plurality of longitudinal axes 94 and a plurality lateral axes 96. The example stud rail assembly 40 defines first, second, and third longitudinal axes 94a, 94b, and 94c, first and second lateral axes 96a and 96b, and first, second, third, fourth, fifth, and sixth intersections 92a, 92b, 92c, 92d, 92f, and 92e. In the example stud rail assembly 40, each of the example inter-

sections 92a, 92b, 92c, 92d, 92f, and 92e correspond to one of the example support assemblies 54a, 54b, 54c, 54d, 54e, and 54f. Grids with different numbers of longitudinal axes, lateral axes, and intersection points may be used depending on the structural requirements of the completed reinforced concrete structure 30.

The folded configuration allows the example stud rail assembly 40 to be stored and shipped in a smaller form factor. The expanded configuration allows the example stud rail assembly 40 to be used, by itself or with one or more other stud rail assemblies, such as the example stud rail assemblies 40b, 40c, and 40d, to form a stud rail system, such as the example stud rail system 20.

The example plurality of support assembly(ies) 54 will now be described in further detail. In addition to engaging the support projections 70 to join the rail portion(s) 50 to the cross portion(s) 52, the example plurality of support assembly(ies) 54 are, as shown in FIGS. 3A, 4A, 5A, and 6A, also configured to space the stud rail assemblies 40a, 40b, 40c, and 40d a predetermined distance D from the surface 28 of the form 24. The example support assembly(ies) 54 are further configured to allow the stud rail assemblies 40a, 40b, 40c, and 40d to be secured in a predetermined configuration relative to the first column portion 22 and to the form 24.

The plurality of rail portion(s) 50 and the plurality of cross portion(s) 52 are typically made of a material capable of reinforcing the completed reinforced concrete structure 30 as determined by the structural requirements of the completed reinforced concrete structure 30. The example plurality of rail portion(s) 50 and plurality of cross portion(s) 52 are thus preferably made of a structural material such as steel, but other materials, coated or uncoated, having similar properties to those of steel may be used in addition or instead. Alternative materials from which the support member(s) 120 may be made include plastic, composite materials such as carbon composites, and the like.

The example support assembly(ies) 54 may comprises a support member 120 and a fastener 122 as shown in FIGS. 12 and 13. The support members 120 forming the example plurality of support assemblies 54 are all the same but may be different. The example support members 120 each comprises a central portion 130, a connecting portion 132, and at least one engaging portion 134.

The example central portion 130 defines a connecting opening 140 defining a connecting axis C. At least a portion of the connecting opening 140 is threaded (not shown). The central portion 130 may be formed in many different sizes and configurations. The example central portion 130 is cylinder. The example connecting portion 132 is in the form of a nut structure 150 that is coaxially aligned with the connecting axis C. The example nut structure 150 may be integrally formed with or secured to the central portion 130.

The engaging portion 134 comprises at least one leg portion 160 extending from the central portion 130 radially outwardly from the connecting axis C. Each leg portion 160 defines at least one foot portion 162, and each foot portion 162 defines at least one fastener opening 164. The example engaging portion 134 comprises first, second, and third leg portions 160a, 160b, and 160c radially extending at equally spaced angles about the connecting axis C.

The example fastener(s) 122 is or may be a nail, screw, or the like that may be extended partly through the fastener opening(s) 164 and into the form 24. The fastener(s) 122 are used to secure the first example stud rail system 20 in a desired position and configuration relative to the first col-

umn portion 22 and the form 24 before and during the pouring of concrete to form the slab 36 and/or second column portion 38.

As perhaps best shown in FIG. 9, the example support member(s) 120 define a height dimension H. When the support member(s) 120 are secured to the support projection(s) 70 to secure the plurality of cross portion(s) 52 to the plurality of rail portion(s) 50, the height dimension H determines a spacing between the form upper surface 28 and a bottom of the stud rail assemblies 40. This spacing, and thus the height dimension H of the support members 120, is predetermined based on the structural requirements of the completed reinforced concrete structure 30.

When embedded within the slab 36, the support member(s) 120 are configured to inhibit or prevent water reaching the stud rail system 20. The example support member(s) 120 are thus preferably made of or coated with a material that inhibits oxidation of the support member(s) 120. A typical material from which the support member(s) 120 is made is plastic, but other materials, coated or uncoated, having similar properties as plastic may be used in addition or instead. In an example embodiment, the support member(s) 120 are plastic so the support member(s) 120 won't corrode and prevent water from getting up into the metal stud rail system 20. Similarly, when fully inserted into the fastener opening(s) 164, the fastener(s) 122 are spaced from the example stud rail system 20 such that water is inhibited or prevented from reaching any components of the example stud rail system 20 that are susceptible to oxidation.

To attach the support member(s) 120 to the example plurality of stud rail assembly(ies) 40, to the support projection(s) 70 is(are) inserted at least partly into the connecting opening(s) 140 such that the threaded external surface(s) 72 of the support projection(s) 70 engage the threaded internal surface portions of the connecting openings 140. The threaded internal surface portions may be formed by the nut structure in the form of a metal nut secured to the support member 120.

Rotation of the support member(s) 120 causes the threaded surfaces to engage each other such that the support member(s) 120 is secured relative to the support projection(s) 70. The nut structure 150 may be engaged to facilitate tightening of the support member(s) 120 onto the support projection(s) 70. Fastening system other than complementary threaded surfaces may be used to secure the support member(s) 120 to the support projection(s) 70.

What is claimed is:

1. A stud rail system for a reinforced concrete structure defining a column portion and a slab portion, the stud rail system comprising:

at least one stud rail assembly comprising

a plurality of rail portions,

a plurality of cross portions, where a plurality of sets of support openings are formed in each of the plurality of the cross portions,

a plurality of pin projections, where each rail portion supports at least one pin projection,

a plurality of support assemblies, and

a plurality of support projections, where each support projection is supported by one of the plurality of support assemblies; wherein

each of the support projections extends through one of the support openings in each set of support openings such that the rail portions are rotatably connected to cross portions at a plurality of axis points to allow the stud rail assembly to be reconfigured between a collapsed configuration and an expanded configuration;

before and during pouring of concrete to form the slab portion, the at least one stud rail assembly is arranged at a desired location and orientation relative to the column portion; and

when supported at the desired location and orientation during pouring of the concrete slab portion, the at least one stud rail assembly is arranged within the slab portion such that at least the cross portions, the pin projections, the support projections, and the support openings of each stud rail assembly are outside an area above the column portion.

2. The stud rail system of claim 1, wherein each pin projection comprises a rod portion and a cap portion.

3. The stud rail system of claim 2, wherein the rod portion defines a first diameter and the cap portion defines a second diameter.

4. The stud rail system of claim 3, wherein the second diameter is greater than the first diameter.

5. The stud rail system of claim 1, in which each set of support openings comprises at least one support opening.

6. The stud rail system of claim 5, in which each support assembly comprises a support member and at least one fastener, where each support member defines a nut structure configured to engage one of the plurality of support projections.

7. The stud rail system of claim 1, in which each set of support openings comprises a plurality of support openings.

8. The stud rail system of claim 1, in which each set of support openings comprises at least two support openings.

9. The stud rail system of claim 1, wherein each support assembly comprises a support member and at least one fastener.

10. The stud rail system of claim 9, wherein the at least one fastener is configured to support the stud rail system in the desired orientation relative to the column portion before and during pouring of concrete to form the slab portion.

11. The stud rail system of claim 9, wherein each support member is configured to prevent water from reaching the at least one rail portion and the at least one cross portion after pouring of concrete to form the slab portion.

12. A method of reinforcing a concrete structure comprising a column portion and a slab portion, the method comprising the steps of:

providing a form;

providing a plurality of rail portions;

providing a plurality of cross portions;

forming a plurality of sets of support openings in each of the plurality of the cross portions;

providing a plurality of pin projections on each of the plurality of rail portions;

providing a plurality of support assemblies;

providing a plurality of support projections;

supporting each support projection by one of the plurality of support assemblies;

forming at least one stud rail assembly by arranging each of the plurality of support projections within one of the support openings of each set of support openings such that the rail portions are rotatably connected to the cross portions at a plurality of axis points to allow the stud rail assembly to be reconfigured between a collapsed configuration and an expanded configuration; before and during pouring of concrete to form the slab portion, arranging the at least one stud rail assembly such that the at least one stud rail assembly is supported at a desired location and orientation relative to the column portion; and

arranging concrete on the form around the stud rail system in the desired location and orientation to form the slab portion such that at least the cross portions, the pin projections, the support projections, and the support openings of each stud rail assembly are outside an area above the column portion.

13. The method of claim 12, in which each set of support openings comprises at least one support opening.

14. The method of claim 12, in which each set of support openings comprises at least one support opening.

15. The method of claim 12, in which each set of support openings comprises a plurality of support openings.

16. The method of claim 12, in which each set of support openings comprises at least two support openings.

17. A reinforced concrete structure comprising:
 a column portion;
 a slab portion;
 a stud system comprising a plurality of stud rail assemblies, where each of the plurality of stud rail assemblies comprises
 a plurality of rail portions,
 a plurality of cross portions, where a plurality of sets of support openings are formed in each of the plurality of the cross portions,
 a plurality of pin projections each supported by one of the plurality of rail portions,
 a plurality of support assemblies,
 a plurality of support projections, where each of the support assemblies supports one of the plurality of support projections; wherein

5

10

25

each of the support projections extends through one of the support openings in each set of support openings such that the rail portions are rotatably connected to the cross portions at a plurality of axis points to allow the stud rail assembly to be reconfigured between a collapsed configuration and an expanded configuration;

before and during pouring of concrete to form the slab portion, the stud system is arranged to support the plurality of stud rail assemblies at desired locations and orientations relative to the column portion; and

when supported at the desired locations and orientations during pouring of the concrete slab portion, the plurality of stud rail assemblies is arranged within the slab portion such that at least the cross portions, the pin projections, the support projections, and the support openings of each stud rail assembly are outside an area above the column portion.

18. The reinforced concrete structure of claim 17, in which each set of support openings comprises at least one support opening.

19. The reinforced concrete structure of claim 17, in which each set of support openings comprises a plurality of support openings.

20. The reinforced concrete structure of claim 17, in which each set of support openings comprises at least two support openings.
